(57) **CLAIM**

We claim the ornamental design for a light-emitting diode (LED) module, as substantially shown and described.

DESCRIPTION

FIGS. 1-7 are various views of a light-emitting diode (LED) module in accordance with the present design.

FIG. 1 is a perspective view of a light-emitting diode (LED) module in accordance with the present design. The broken lines depict portions of the light-emitting diode (LED) module that form no part of the claimed design.

FIG. 2 is a top view of the light-emitting diode (LED) module shown in FIG. 1. The broken lines depict portions of the light-emitting diode (LED) module that form no part of the claimed design.

FIG. 3 is a bottom view of the light-emitting diode (LED) module shown in FIG. 1. The broken lines depict portions of the light-emitting diode (LED) module that form no part of the claimed design.

FIG. 4 is a front view of the light-emitting diode (LED) module shown in FIG. 1.

FIG. 5 is a rear view of the light-emitting diode (LED) module shown in FIG. 1.

FIG. 6 is a left view of the light-emitting diode (LED) module shown in FIG. 1; and,

FIG. 7 is a right view of the light-emitting diode (LED) module shown in FIG. 1.

The broken lines depict portions of the light-emitting diode (LED) module that form no part of the claimed design.
